UNITED STATES PATENT OFFICE.

HARRY LITVAK, OF HUDSON, NEW YORK.

FOLDING BED.

1,401,714.

Specification of Letters Patent. Patented Dec. 27, 1921.

Application filed March 10, 1921. Serial No. 451,086.

To all whom it may concern:

Be it known that I, HARRY LITVAK, citizen of the United States, and resident of the city of Hudson, in the county of Columbia and State of New York, have invented 5 certain new and useful Improvements in Folding Beds, of which the following is a specification.

This invention relates to a tension device 10 for bed springs. More particularly, this invention relates to a device for positioning and tensioning a bed spring on a bedstead.

One object thereof is to provide a device 15 of the character described adapted to position the bed spring in place on the bed.

Another object is to provide a device of 20 the character described adapted to tension the bed spring for the taking up of any slack or sag.

Other objects of this invention will be in 25 part obvious and in part hereinafter pointed out.

The invention accordingly consists in the features of construction, combinations of 30 elements and arrangement of parts which will be exemplified in the construction hereinafter described and of which the scope of invention will be indicated in the following claims.

In the accompanying drawings, in which 35 is shown one of various possible illustrative embodiments of this invention,

Figure 1 is a side elevational view of a 40 folding bed embodying this invention with the spring in place thereon and the device for placing and tensioning the same on the bed attached thereto;

Fig. 2 is a partial plan view corresponding 45 to Fig. 1;

Fig. 3 is an enlarged partial side elevational view showing the tensioning and 50 positioning mechanism for the spring;

Fig. 4 is an end elevational view of the 55 folding bed shown in Fig. 1.

Referring in detail to the drawing, the 60 embodiment of the invention there shown as attached to a bed comprising two pairs of end posts 10 having leg portions 11. Secured to these end posts as by means of the 65 removable bolts 12 provided with wing nuts 13 are a pair of side rails 14. A bottom cross piece 20 is secured as by means of bolts 21 to each pair of end posts 10 beneath the side rails 14. A similar top cross 70 piece 23 is secured at the top of each pair of end posts. Extending between the end

pieces and over the side rails is the usual wire spring 24 which is secured in position and tensioned in a manner now to be described by means of my novel apparatus. 60

Detachably secured, preferably at each end of the bed, is a housing 25 in which is assembled the mechanism for drawing the spring on to the bed and tensioning the same. The four housings are secured in 65

the form shown in the drawing both to the side rails as by the removable bolt 26 and nut 27 thereof, and to the end posts by means of the removable bolts 28 and wing nuts 28'. The mechanism comprises a shaft 70

29 extending cross-wise of the bed journaled as at 30 in the pair of opposed housings 25, secured to each pair of the end posts as shown in Fig. 4. Mounted on this shaft is a gear 31 and a ratchet wheel 32. A pawl 75

33 is suitably pivoted as at 34 in operative relation to this ratchet wheel. Another shaft 35 similarly journaled in the pair of opposed housings 25 to extend parallel to the shaft 29 is provided with a handle 36 and 80

carries a gear 37 arranged and adapted to mesh with the gear 31. A pawl 38 suitably pivoted as at 39 is provided for this gear 37. A spring 40 provided in connection with 85

each of the shafts 35 is secured at one end as at 41 to each of the side rails 14, while its free end is secured to the shaft 35 as at 42 by means of a flexible connection such as a 90

chain or cord 43 passing into each housing. The shaft 29 is provided with pins 44 adapted to engage the mesh of the wire spring 24. 95

The operation of the device in practice is as follows: The shaft 35 is first revolved thus winding thereon the chains 43 against the tension of the springs 40. When the springs 40 have been fully extended the pawl 33 is allowed to drop in place in the ratchet wheel 32 thus preventing the unwinding of 100

the chains, and holding stationary the gears 31 on the shafts 29. The bed spring is then attached to shaft 29 in the manner described 105

and the pawl 33 lifted thus releasing the gear 31 which now rotates in a direction opposite to the direction in which shaft 29 has been operated by reason of the return action of 110

the springs 40. The shaft 35 in turn rotates in the same direction as the shafts 29 being driven by the gear wheel 37 which meshes with the gear wheel 31, and thus winding 115

the spring on the shafts 29 and tensioning the same. The pawl 38 may be dispensed with but is preferably provided as an extra

check to prevent unwinding of the shafts 35 before the bed spring has been secured to the shafts 29.

It will thus be seen that there is provided apparatus in which the several objects of this invention are achieved and which is well adapted to meet the conditions of practical use.

As various possible embodiments might be 10 made of the above invention and as various changes might be made in the embodiment above set forth, it is to be understood that all matter herein set forth or shown in the accompanying drawings is to be interpreted 15 as illustrative and not in a limiting sense.

Having thus described my invention, I claim as new and desire to secure by Letters Patent:—

1. In combination with a bed having end 20 posts and side rails, means for tensioning a bed spring in place on said bed, said means comprising a housing attached to said end posts, a shaft journaled transversely of said side rails within said housing, means for 25 operating said shaft, and a tension device in connection with said shaft adapted to be energized by the operation of said shaft as and for the purpose herein specified.

2. In combination with a bed having end 30 posts and side rails, means for tensioning a bed spring in place on said bed, said means comprising a housing attached to said end posts, a main shaft journaled transversely of said side rails within said housing, a 35 countershaft operated from said main shaft, means on said countershaft for attaching a bed spring thereto and a tension device in connection with said main shaft adapted to be energized by the operation of said main 40 shaft, as and for the purpose herein described.

3. In combination with a bed having end posts and side rails, means for tensioning a bed spring in place on said bed, said means 45 comprising a housing attached to said end posts, a main shaft journaled transversely of said side rails within said housing, a

countershaft operated from said main shaft, means on said countershaft for attaching a bed spring thereto and a tension device in connection with said main shaft adapted to be energized by the operation of said main shaft, means for transmitting said motion from said main shaft to said countershaft, means for locking said motion transmitting means against operation, and means for releasing said motion transmitting means for operation by said tension device. 50

4. In combination with a bed having end 60 posts and side rails, means for tensioning a bed spring in place on said bed, said means comprising a housing attached to said end posts, a main shaft journaled transversely of said side rails within said housing, a countershaft operated from said main shaft, 65 means on said countershaft for attaching a bed spring thereto and a tension device in connection with said main shaft adapted to be energized by the operation of said main shaft, intermeshing gear wheels carried by 70 said shafts, means for locking said gear wheels against rotation during the application of power to the main shaft, and means for releasing said gears to impart rotation to said counter-shaft by said tensioning 75 device.

5. A device for positioning and tensioning a bed spring on a bedstead comprising a casing adapted to be attached to the bedstead, means extending from said casing 80 adapted to receive one end of the bed spring, and a power mechanism for mechanically winding and tensioning said bed spring in position, said power mechanism including an energy storing device adapted to be released for operation to wind and tension the bed spring in position. 85

Signed at the city of Hudson, in the county of Columbia and State of New York, this 25th day of January A. D. 1921.

HARRY LITVAK.

Witness:

Wm. WALLACE CHACE.
